UNITED STATES PATENT OFFICE

150,366

DESIGN FOR A VENTILATING UNIT

John Brandt Koch, Detroit, Mich., assignor to
American Blower Corporation, Wilmington,
Del., a corporation of Delaware

Application August 7, 1946, Serial No. 132,346

Term of patent 14 years

(Cl. D62—4)

To all whom it may concern:

Be it known that I, John Brandt Koch, a citizen of the United States, residing at Detroit, in the county of Wayne and State of Michigan, have invented a new, original, and ornamental Design for a Ventilating Unit, of which the following is a specification, reference being had to the accompanying drawing, forming a part thereof, wherein:

Figure 1 is a front perspective view of a ventilating unit, showing my new design.

Figure 2 is a front elevational view of the ventilating unit;

Figure 3 is a side elevational view of the ventilating unit;

Figure 4 is a rear perspective view thereof with the rear cover in open position.

The dominant features of my design reside in the portions shown in full lines.

I claim:

The ornamental design for a ventilating unit, substantially as shown and described.

JOHN BRANDT KOCH.
